CIGARETTE CASE AND DISPENSER

George H. Huttaff, Jr., Wilmington, N. C.

Application September 17, 1938, Serial No. 230,496

7 Claims. (Cl. 312—78)

My invention relates to new and useful improvements in cigarette case and dispenser and in so far as there is common subject matter is a continuation in part of my application filed 5 November 4, 1937, Serial No. 172,795, issued August 1, 1939, as Patent No. 2,168,214.

The principal object of the present invention resides in the provision of a device of the character described in which provision is made for 10 storing a number of cigarettes and dispensing a single cigarette at a time at the desire of the user, a lid or cover being provided for normally closing the case, but adapted to be raised for placing the cigarettes therein or depressed from its normal horizontal closing position for dispensing the cigarettes.

Another object of the invention consists in the provision of novel means for operating a slidable plunger which dispenses a single cigarette at a 15 time through a horizontally positioned elongated opening in the front face of the case, said operating means including the hinged cover or closure of the case and a vertically extending slid- 20 able member, said slidable member being nor- mally held in its raised position to form a sup- port for holding the lid or cover in a substan- tially horizontal position, the lid or cover being 25 pivotally connected to the body portion of the case in such a manner that it may be swung up- 30 wardly from its horizontal position or depressed therefrom, the depressing movement thereof oper- 35 erating the vertically extending slidable member to in turn operate the slidable plunger for dispensing the cigarettes.

A still further object of the invention consists 40 in changing the position of the dispensed cigarette as it is discharged through the elongated horizontal opening of the case, the cigarette being normally positioned to extend parallel with the elongated opening but in its discharge movement through the opening being turned to project forwardly of the case in a position to be engaged and withdrawn by the user.

With the above and other objects in view, which 45 will appear as my description proceeds, my invention consists in the novel details of construction, and arrangement of parts, described in the following specification and illustrated in the accompanying drawing, and while I have illustrated 50 and described the preferred embodiments of the invention, as they now appear to me, it will be understood that such changes may be made as will fall within the scope of the appended claims.

55 In the drawing—

Fig. 1 is a perspective.

Fig. 2 is a transverse vertical section on the line 2—2 of Fig. 4 looking in the direction of the arrows with the cover or lid in position.

Fig. 3 is a vertical section on the line 3—3 of 5 Fig. 2 looking in the direction of the arrows.

Fig. 4 is a horizontal section on the line 4—4 of Fig. 2 looking in the direction of the arrows; and

Fig. 5 is a detailed perspective of the operating 10 means or plate for the slidable dispensing plunger.

In carrying forward my invention I provide a box-like structure including a front plate 1 having a horizontally extending elongated opening 2 15 therein, side plates 3, rear plate 4, and bottom 5, the bottom 5 being provided with the openings 6 and 7 for a purpose which will be presently brought out. A lid or cover 8 is pivotally connected, by pin hinges 9, to be normally positioned 20 between the front, back and side plates 3 with its upper surface on a plane flush with the upper edges of the plates and secured to this lid or cover, adjacent its free edge, is a knob or hand-hold 10 for manipulation thereof. By the pin connections 25 9 the lid or cover may be raised to supply the box-like structure or receptacle with cigarettes or may be depressed into the position shown by dotted lines in Fig. 2 for dispensing a single cigarette in a manner which will be presently brought out. 30

What might be termed a false bottom or plunger support 11 is positioned slightly above the bottom 5, as shown more particularly in Fig. 2 of the drawing, this false bottom or support being formed with a central opening 12. Slidable on 35 the false bottom or support 11 is a plunger or plunger plate 13 formed at its rear edge with the projecting lugs or ears 14 and the inwardly ex- 40 tending elongated slot 15. Positioned between and supported by the lugs or ears 14 is a roller 16. The plunger or plunger plate 13 is normally held 45 in its forward position by the coiled spring 17, one end of the spring being connected to the eye 18, carried by the false bottom 11, while the opposite end of the spring is connected to the eye 19, car- 50 ried by the plunger or plate 13. When in its for- 55 ward position the front edge of the plunger projects into the elongated opening 2, as shown more particularly in Figs. 1 and 2 of the drawing. Formed in the forward edge of this plunger or plunger plate 13, at one end, is a notch 20, this notch permitting the cigarette, which is being dis- 60 pensed, to turn from a horizontal position parallel with the opening 2 to a position at right angles thereto projected forwardly to be easily grasped. 65

it being understood that in dispensing the end of the cigarette will engage the end 21 of the opening 2 which cooperates to turn the cigarette as described. As this particular feature of the invention forms no particular part of the present invention, and it is described more in detail in my co-pending application, above referred to, a further description will not be given at the present time.

10 Interiorly of the box-like structure or body is provided an inclined platform 22, the lower edge of which terminates inwardly of the front face of the box or receptacle, as shown more particularly in Fig. 2 of the drawing. This platform is 15 provided, adjacent its upper edge, at the rear face 4, with an opening 23 and the purpose of this opening will be later brought out. It will be understood that the cigarettes will be supported on this platform and will roll onto the 20 upper surface of the plunger or plunger plate 13.

For operating the plunger or plunger plate 13 I provide a member including a vertically extending portion 24 having the head 25 at its upper end and the forwardly directed projection 26 25 having the depending portion 27. The lower edge of the projection 26 is inclined, as shown at 28, and engages the roller 16, carried by the plunger or plunger plate 13, as shown more particularly in Fig. 2 of the drawing. The operating member is normally held in its raised position, shown in full lines in Fig. 2, by means of the plunger or plunger plate 13 which is in turn held in its normal forward position by the spring 17. The vertically extending portion 24 passes 30 through the opening 23 in the platform 22 with its lower end received in an opening 29 in the false bottom 11. The head portion 25 normally supports the lid or cover 8 in the horizontal position shown in full lines.

40 It is thought from the above that the detailed construction will be understood and I will now describe the operation more in detail. When it is desired to fill the case with cigarettes the user will grasp the knob or hand-hold 10 and raise 45 the lid or cover 8 upwardly, this movement being permitted by the pivot pins 9. The cigarettes are then placed in the case with a portion received on the platform 22 and others received on the plunger or plunger plate 13, as shown by dotted lines in Fig. 2 of the drawing. After being filled the lid or cover 8 will be returned to its normal horizontal position. When it is desired to dispense a cigarette the user will press down on the knob or hand-hold 10 and this will swing 50 the lid or cover into the position shown by dotted lines in Fig. 2. The downward movement of the lid or cover, engaging the head 25, lowers the portion 24 of the operating member with its forwardly directed extension 26 and this lowering of the operating member will cause the plunger 13 to be moved rearwardly against the action of the coiled spring 17, it being understood that the inclined surface 28 of the extension 26, engaging the roller 16, will cause the plunger to be drawn 55 rearwardly. A single cigarette will drop onto the false bottom or support 11 in front of the plunger or plunger plate 13. When the knob or hand-hold 10 is released the coiled spring 17 will draw the plunger or plunger plate 13 forwardly 60 and discharge a single cigarette through the opening 2, the cigarette being turned as it passes through the opening, in the manner previously described, to project forwardly into position to be grasped and removed by the user. As the plunger or plunger plate 13 moves forwardly, the roller

16 operating over the inclined surface 28, will cause the operating member to be moved into its normally raised position and in turn to raise the lid or cover to its normal horizontal position. When the operating member is lowered the projection 27 will engage in the opening 6 of the bottom 5 while the lower end of the member or portion 24 will enter the opening 7. By providing the false bottom or support 11 with the opening 12 the surface to be engaged by the plunger 10 or plunger plate 13 is reduced and therefore friction is reduced in the operation of the plunger.

Having fully described my invention what I claim as new and desire to secure by Letters Patent is:

1. A combined cigarette case and dispenser including a receptacle having an opening therein, means including a plunger for supporting cigarettes in the receptacle, a movable cover for the receptacle, a plunger support, means controlled 20 by movement of the cover for operating the plunger in a direction to allow a single cigarette to be positioned on the plunger support in front of and parallel with the edge of the plunger, and means for returning the plunger to its initial 25 position and to discharge the cigarette in front of the plunger from the receptacle through the opening therein.

2. A combined cigarette case and dispenser including a receptacle having an opening therein, 30 means including a plunger for supporting cigarettes in the receptacle, a cover pivotally connected to the receptacle and normally held in horizontal position but adapted for movement in both an upward and downward direction from its normal position, a plunger support, means controlled by the downward movement of the cover from its normal position to operate the plunger to position the same to permit a single cigarette to be positioned on the plunger support 40 in front of and parallel with the edge of the plunger, and means for returning the plunger to its normal position and to discharge the cigarette in front of the plunger from the receptacle through the opening therein, the cover when 45 swung in an upward direction from its normal position permitting filling of the receptacle with the cigarettes.

3. A combined cigarette case and dispenser including a receptacle provided with a dispensing 50 opening, means including a plunger for supporting cigarettes in the receptacle, a cover pivotally connected to the receptacle and adapted for movement in both an upward and downward direction from its normal position, a plunger support means interposed between the cover and plunger and operable by downward movement of the cover to in turn operate the plunger to a position to permit a single cigarette to be positioned on the plunger support in front of and parallel 55 with the edge of the plunger, and means for returning the plunger to its initial position to discharge the cigarette in front of the plunger through the dispensing opening in the receptacle, said means interposed between the cover and plunger normally supporting the cover in a horizontal position but permitting the same to be raised from said horizontal position to place cigarettes in the receptacle.

4. A combined cigarette case and dispenser including a receptacle provided with a dispensing opening, means including a plunger for supporting cigarettes in the receptacle, a cover pivotally connected to the receptacle and adapted for movement in both an upward and downward di- 70 75

- rection from its normal position, a plunger support in the receptacle, a vertically slidable member interposed between the cover and plunger, said member normally supporting the cover in a 5 horizontal position but operable upon downward movement of the cover to operate the plunger to a position to permit a single cigarette to be positioned on the plunger support in front of the plunger and parallel with the edge of the plunger, and means for returning the plunger to its 10 normal position to discharge the cigarette in front of the plunger through the dispensing opening of the receptacle.
5. A combined cigarette case and dispenser including a receptacle provided with a dispensing opening, means including a plunger for supporting cigarettes in the receptacle, a cover pivotally connected to the receptacle, a plunger support, a roller carried by the plunger, a member 15 interposed between the cover and plunger and having a beveled portion engageable with the roller of the plunger for operation thereof, said member normally supporting the cover in horizontal position and operable by movement of the 20 cover from its normal position to operate the plunger to a position to permit a single cigarette to be positioned on the plunger support in front of the plunger and parallel with the edge of the plunger, and means for returning the plunger to its 25 normal position to discharge the cigarette in front of the plunger through the dispensing opening of the receptacle.
6. A combined cigarette case and dispenser including a receptacle having a dispensing opening therein, means including a plunger for supporting cigarettes in the receptacle, a cover pivotally connected to the receptacle and adapted for movement in both an upward and downward direction from its normal horizontal position, a plunger 30 support in the receptacle, a roller carried by the plunger, a member slidably interposed between 35 the cover and plunger, said member having a head portion formed on its upper end adapted to engage and support the cover in its normal horizontal position and a forwardly directed portion having a beveled surface engageable with the 40 roller of the plunger for operating the plunger, said interposed member being operated on a downward movement of the cover from its original position to operate the plunger to a position to permit a single cigarette to be positioned on the plunger support in front of and parallel with the edge of the plunger, and means for returning the plunger to its initial position and discharge the single cigarette in front of the plunger through the dispensing opening, the cover when 45 moved in an upward direction from its normal position permitting filling of the receptacle with cigarettes.
7. A combined cigarette case and dispenser including a receptacle having a discharge opening 20 therein, means including a plunger for supporting cigarettes in the receptacle, a plunger support, a cover pivotally connected to the receptacle for swinging movement in an upward or downward direction, a single interposed member 25 for normally supporting the cover in horizontal position and for operating the plunger in a direction, on downward movement of the cover, to permit reception of a single cigarette on the plunger support in front of and parallel with the 30 edge portion of the plunger, and means for returning the plunger to its initial position and to discharge the cigarette in front of the plunger through the opening of the receptacle, the movement of the plunger to its initial position acting 35 through the interposed member to return the cover to its normal horizontal position and to permit the same to be swung upwardly from its horizontal position to permit filling of the receptacle.
